UNITED STATES PATENT OFFICE.

WILLIAM J. GRADY, OF DECATUR, ILLINOIS, ASSIGNOR TO FARIES MANUFACTURING COMPANY, OF DECATUR, ILLINOIS, A CORPORATION OF ILLINOIS.

DESIGN FOR AN ARM FOR LIGHTING FIXTURES.

Application filed January 23, 1922. Serial No. 315. Term of patent 7 years.

To all whom it may concern:

Be it known that I, WILLIAM J. GRADY, a citizen of the United States, residing at Decatur, in the county of Macon and State of Illinois, have invented a new, original, and ornamental Design for Arm for Lighting Fixtures, of which the following is a specification, reference being had to the ac-

companying drawing, forming part thereof.

The figure is a perspective view of my new design.

I claim:

The ornamental design for an arm for lighting fixtures, as shown.

WILLIAM J. GRADY.
